METHOD OF MAKING HUB SHELLS AND LIKE TUBULAR METAL ARTICLES

Application filed January 31, 1929. Serial No. 336,483.

The present invention relates to the manufacture of hub shells and similar articles, and its primary object is to provide a method whereby a more desirable distribution of the 5 constituent metal can be obtained.

More particularly, our invention contemplates a process which involves the circularizing or tubulating of a flat or substantially flat blank of a suitable metal such as steel, and 10 the then working and forming of the resulting tube in such a manner as to obtain some predetermined distribution and structure of the metal in the article being produced. In one form of this process, a tube having walls 15 of substantially uniform thickness is partly reduced in diameter in order to provide additional metal for subsequent reworking into features which are required to possess unusual physical properties; and in another 20 form a tube having walls of unequal thickness is directly worked in order to provide the desired distribution. The especial parts which it is intended to thus improve are those sections with which the inner ends of the 25 spokes engage; but in the making of articles other than hub shells for wire spoked wheels, the details of our provided method can be altered with a view to reinforcing any particular part. As in any case the working required 30 for obtaining the particular shape desired is carried out in a circumferential direction, our method presents a further advantage in that the fibers of the metal are arranged with their axes at right angles to the longitudinal axis 35 of the article as a whole; and this disposition of such fibers further increases or improves the advantages which attend the distribution obtained in the above explained manner. In both of the methods just described, the results 40 desired are gotten without its being necessary to use a heavier grade of stock; and this advantage in association with the improved physical characteristics produced by the additional working, and with the convenience, 45 inexpensiveness and adaptability of the gen-

eral process makes our method superior to the others which are employed for generally similar purposes.

To the accomplishment of the foregoing and related ends, said invention, then, consists of the means hereinafter fully described and particularly pointed out in the claims; the annexed drawings and the following description setting forth in detail one approved mode of carrying out the invention, such disclosed mode, however, constituting but one of the various ways in which the principle of the invention may be used.

In said annexed drawings:—

Fig. 1 is a perspective view of a blank of the kind which we may employ; Figs. 2, 3 and 4 are perspective views which illustrate the various steps involved in the tubulating of the blank shown in Fig. 1; Figs. 5 to 9, inclusive, are partly sectional and partly elevational views which illustrate the successive operations employed for transforming the tube shown in Fig. 4 into the finished article; and Fig. 10 is a perspective view of a modified blank.

In the practice of our invention, a substantially flat and generally rectangular blank of the kind shown in Fig. 1 is first circularized to produce the open ended hoop illustrated in Fig. 2. The ends 10 of this hoop are then 75 heated to a sufficiently high temperature and forced into the upset weld 11 (Fig. 3). Following this, the flash or bur 12 is removed; and the article then presents the appearance shown in Fig. 4. In the next operation (Fig. 5), the outer end 13 is reduced in diameter to form the relatively smaller section 14; and in the immediately succeeding operation such section is curled as at 15 and the inner end 16 is expanded or radially enlarged (Fig. 6). 85 The operations described in connection with Fig. 6 are, in a sense, only preliminary to the operations which result in the article shown in Fig. 7; in other words, the former operations are effected with a view to roughly 90

forming the article so that it can be accurately shaped and dimensioned by the latter operations. This last mentioned operation, in addition to sizing the outer end of the article, also forms the intermediate angular part 17; and, if desired, such sizing and forming may consist of a primary rolling followed by a secondary shrinking or contracting. In the next succeeding operation, the inner section 16 is flared in the manner shown in Fig. 8; and in the following operation, the flange 18 is given the final contour shown in Fig. 9, and its inner end is coined as at 19. In the article as so finished, the curl or corrugation 15 at the outer end and the outwardly flaring part 20 at the inner end serve as anchors for the spokes which are assembled with the hub and felly.

The above explained operations can be effected by any suitable apparatus; for example, the blank shown in Fig. 1 can be sheared to the desired size and shape in a punch press or by means of any other machine adapted to this end; the hoop shown in Fig. 2 can be produced on a rolling machine having three pyramidically arranged rolls, or it may be formed by bumping or rounding on a press or bulldozer between dies; the ring illustrated in Fig. 3 is preferably produced by electric welding; the bur or flash incident to the welding is removed by shearing and grinding; the reduction of the outer end of the article (Fig. 5) may be effected in a machine provided with a multiplicity of shrinking blocks or dies; the further forming represented in Fig. 6 is effected by means of a special expanding chuck and shaping dies; the form shown in Fig. 7 may be imparted by the use of a two-roll rolling machine primarily and by the use of a shrinking machine secondarily; the succeeding flaring operations (Fig. 8) may be effected by suitable dies; and the final form illustrated in Fig. 9 may be imparted by the use of an apparatus similar to that employed in effecting the immediately preceding operation.

From the above description of one form of our improved method, it will be apparent that the shrinking operation is the primary means of obtaining the desired redistribution of the metal of the walls of the tubular blank; as an alternative means of obtaining a more satisfactory distribution of such metal, a blank of the kind shown in Fig. 10 may be employed. This blank has two portions of different thickness, and when it is rolled into a tube and then formed and shaped in the manner above explained, the thicker portion 21 will provide adequate metal for a part corresponding to the bulge 15, and the thinner part 22 will similarly provide adequate metal for a portion corresponding to the flange 18. The forming and shaping operations may be substantially the same as those explained in connection with the

making of an article from a blank of uniform thickness, but as before stated the shrinking operation may be omitted. The working and lengthwise shortening of the tube in this latter method of practicing our invention presents the same advantages as have already been noted; in other words, these operations are effective to increase the strength of the metal and to improve its suitability to particular ends and for specific purposes.

The stock used in connection with our present method should desirably be so cut or selected that in the finished article the long axes of its fibers will extend circumferentially. In other words, it is preferable that such axes should be disposed in a direction coincident with the direction in which the major part of the working occurs; and if this is the fact, such disposition or arrangement of the fibers, and the working necessary for completing the shaping, will supplement each other in the production of a generally improved article. In some cases, this working is effected in opposite directions from dimensions intermediate in magnitude between the dimensions of the different parts of the finished article, but in general such final size and shape are determined by the character of the article being made and by the preliminary forming operations, these latter of course being variable according to the particular form desired.

Other modes of applying the principle of our invention may be employed instead of the one explained, change being made as regards the method herein disclosed, provided the step or steps stated by any of the following claims or the equivalent of such stated step or steps be employed.

We therefore particularly point out and distinctly claim as our invention:—

1. In the manufacture of tubular articles of variant diameter, the method which consists in providing a tube, reducing the diameter and circularly corrugating one terminal portion of such tube and then enlarging the diameter of the other terminal portion of such tube.

2. In the manufacture of tubular articles of variant diameter, the method which consists in reducing the diameter of one terminal portion of a tube, in circumferentially bulging the end of such portion, and in then flaring the other terminal portion of such tube.

3. In the manufacture of tubular articles, the method which consists in providing a tube having a wall of diminishing thickness, forming a circumferential bulge in the thick part of such wall, and flaring the thin part of such wall.

4. The method which consists in tubulating a blank, in reducing one end of such tube,

circumferentially corrugating such reduced end, and flanging the other end.

5. The method which consists in providing a tube, reducing one end of such tube, corrugating such reduced end, flaring the other end, flaring the part intermediate such ends, still further flaring such other end, and then coining the part of such other end as so flared.

10. The method which consists in providing a tube having walls which are thick at one end and thin at the other end, and then respectively outwardly curling and flanging such ends.

15. The method of making shells for wire spoked wheels which consists in tubulating a blank, welding the adjacent edges of such tube, and then providing the end portions of the resulting article with enlargements for anchoring the inner ends of the spokes.

20. 8. The method which consists in tubulating a blank, shrinking one end of such tube, forming such shrunk end into an anchorage for the outer series of the spokes of a wire strung wheel, and forming the other end of 25 such tube into an anchorage for the inner series of the spokes of such a wheel.

9. The method which consists in providing a tube-like blank, locally thickening the metal of such blank, annularly bulging such 30 thickened portion and then forming such bulged portion into spoke anchorages.

10. In the manufacture of tubular metal articles of varying diameter, the steps which consist in reducing the diameter of one end 35 of a substantially cylindrical tube to provide an increased thickness of metal, and then working such metal outwardly to form an inwardly directed groove in such end.

11. In the manufacture of tubular metal 40 articles of varying diameter, the steps which consist in reducing the diameter of one end of a substantially cylindrical tube to provide an increased thickness of metal, working such metal outwardly to form an inwardly directed groove in such end, and working the metal of the other end outwardly to form a flange.

12. In the manufacture of tubular metal 45 articles of varying diameter, the steps which consist in reducing the diameter of one end of a substantially cylindrical tube to provide an increased thickness of metal, and then working such end outwardly to form an inwardly directed groove and an inwardly directed flange.

13. In the manufacture of tubular metal 50 articles of varying diameter, the steps which consist in reducing the diameter of one end of a substantially cylindrical tube to provide an increased thickness of metal, working such metal outwardly to form an inwardly directed groove in such end, and flaring such tube from such groove towards the other end.

14. The method which consists in tubulating a metal strip, in welding the edges of

such tube, bulging the end portions of such tube and then forming such bulged portions into anchorages for the spokes of a wire strung wheel.

15. The method which consists in providing a tube-like blank, thickening parts of such blank, and then rolling portions of such thickened parts to provide outwardly directed projections.

Signed by us, this 28th day of January, 75
1929.

HARRY W. KRANZ.
